UNITED STATES PATENT OFFICE.

ISAAC KARPEN, OF CHICAGO, ILLINOIS, ASSIGNOR TO S. KARPEN & BROS., OF CHICAGO,
ILLINOIS, A CORPORATION OF WEST VIRGINIA.

UPHOLSTERING-MACHINE.

No. 931,313.

Specification of Letters Patent. Patented Aug. 17, 1909.

Application filed August 24, 1907. Serial No. 390,025.

To all whom it may concern:

Be it known that I, ISAAC KARPEN, a citizen of the United States, residing at Chicago, in the county of Cook and State of Illinois, have invented a new and useful Improvement in Upholstering-Machines, of which the following is a specification.

My invention constitutes an improvement on the upholstering machine described and 10 claimed in my application No. 390,024, filed of even date herewith.

My primary object is to provide improved fastener-holding means for use in connection with a machine of the character indicated.

The invention is illustrated in the accompanying drawing, in which—

Figure 1 represents a broken sectional view of a mold of a tufting machine having 20 its presser-board, or follower, equipped with my improved fastener-holding means; Fig. 2, a similar view showing an edge-rail of the mold removed and the covering of the mattress, or pad, turned up for connection with the fasteners; Fig. 3, a broken edge view of 25 the follower with the improved fastener-holding means applied thereto and fasteners held thereby; Fig. 4, a perspective view of one of the fastener-guides employed; and 30 Fig. 5, a broken perspective view of the follower and one of the retainer-bar guides employed.

In the drawing, A represents the mold of a tufting-machine, having a bottom A¹ and 35 a removable edge-rail A²; B, the follower of the mold; and C, my improved fastener-holding means applied to the edge of the follower.

The fastener-holding means C comprises 40 vertically disposed fastener-guides c having attaching flanges c¹ at their upper and lower ends and provided with T-slots c² for receiving the fasteners c³; retainer-rods c⁴ adapted to cross the open channels of the 45 T-slots and spaced to receive between them the shanks of the fasteners; and retainer-rod-guides c⁵ applied to the edge of the follower-board, as by screws c⁶, said guides c⁵

being provided with horizontal channels c⁷ disposed to space the rods so as to accommodate the shanks of the fasteners. The upper and lower margins of the follower-board B are recessed to receive the flanges c¹ of the members c and said members are secured to the board by screws c⁸. 50 55

As described in the above-mentioned application, the heads of the fasteners are received in the guides c, the points projecting outwardly. One retainer-rod is withdrawn to permit the fasteners to be dropped into their guides, after which said rod is inserted to secure the fasteners in place. D represents a mattress, or pad, (inverted during tufting) having an inner fabric (usually canvas) d, an outer covering (usually 60 leather or imitation leather) d¹, and a fringe or flap d². As is known, the margins of these fabrics are preparatorily perforated to receive the fasteners. After the fasteners are entered and clenched, the lower retainer rod is withdrawn and the follower is lifted 65 from the pad. 70

In practice, the members c are formed from sheet-metal, and the members c⁵ are cast. It is observed that the members c⁵ and 75 their channels are deep enough to permit the rods c⁴ to lie outside or across the members c.

What I regard as new, and desire to secure 80 by Letters Patent, is—

1. In means of the character set forth, the combination with a follower, of sheet-metal members formed with T-slots therein and equipped with means for attachment to an edge of the follower, retainer-rods crossing 85 said slots, and guides for said retainer-rods applied to an edge of said follower.

2. A fastener-guide clip for the purpose set forth, comprising a member adapted to extend cross-wise of the edge of a follower-board and formed with a T-slot therein and with attaching flanges at its ends. 90

ISAAC KARPEN.
